Frederick Schultz of the District of Northern Liberties, Pa.

Assignor to

William P. Cameron of Philadelphia, Pa.

Letters Patent No 484 Dated Aug. 10th 1852

The schedule referred to in these Letters Patent and making part of the same

To all whom it may concern:

Be it known that I, Frederick Schultz of the District of Northern Liberties, in the County of Philadelphia, and State of Pennsylvania, have invented or produced a sett of new & original designs to ornament a Flat Top Cooking Stove, and I do hereby declare that the following is a full and exact description of the same.

Fig 1 Represents a front plate the lower portion of each end is ornamented with a panel, in the centre of which is a skeleton vase, from which is a grape vine ascending with leaves and fruit as at a, a. The space between the panels is occupied with folding doors paneled with bead work, across the top of each door a double panel of bead work as at c c c c above which is raised an abutment as at E.

Fig 2 Represents a side plate, one of the upper corners of which is ornamented with raised panels, around which is bead work

2

Des. 484

as at d,d,d,d, in the centre of which are two diamond shaped crosses as at f, below this panel is a square door formed with the panels and bead work as at b,b,b,b, in the centre of which are two diamond shaped crosses as at g. To the side of the door just described is a larger door ornamented with raised panels & bead work as at i,i,i,i, in the centre of which is scroll work leaves and flower work as at h,h,h,h, above the door just described is a raised panel and bead work as at l,l,l,l, across the bottom of the plate is a panel and bead work extending the width of both doors, within which is the words & figures

Globe Improved Patented 1852

as at H. Fig 3 Represents the back plate ornamented with a succession of raised panels and bead work as at K K K L L L.

What I claim as my invention and desire to secure by Letters Patent is the ornamental designs for a Flat Top looking Stove as herein described and arranged and represented in the annexed drawing
